1,544,357

UNITED STATES PATENT OFFICE.

CHARLES J. THATCHER, OF NEW YORK, N. Y.

ELECTROLYTIC PROCESS.

No Drawing.

Application filed April 2, 1923; Serial No. 629,419.

To all whom it may concern:

Be it known that I, CHARLES J. THATCHER, a citizen of the United States, and a resident of New York, in the county of New York and State of New York, have invented 5 certain new and useful Improvements in Electrolytic Processes, of which the following is a specification.

The invention relates to electrolytic processes; and its object is to prepare a plurality of products, particularly organic products, by one electrolysis.

By way of example, the novel process will be described as applied to the production of 15 anthraquinone from anthracene and of benzidine from azoxybenzol or azobenzol. It is to be understood, however, that the process may be applied to the oxidation and reduction, by one electrolysis, of other compounds, either organic or inorganic, and 20 which are either solid or liquid, and either insoluble or soluble in the electrolyte used—provided the products resulting from the electrolysis can be substantially completely 25 separated from the respective anolyte and catholyte after each operation or series of operations.

Apparatus suitable for this purpose may consist of a single cell adapted to maintain 30 effective separation of the anolyte and catholyte liquors, as by a diaphragm of the character, for example, set forth in my U. S. Letters Patent No. 1,291,253. Or, as described and shown in my U. S. Letters Patent No. 35 1,397,562, the apparatus may consist of a plurality of electrolytic cells connected preferably in series or series parallel, and having separated anode and cathode compartments. The cells should preferably be of 40 a type providing for vigorous agitation of the electrolyte, and in which the agitation tends to maintain a homogenous mixture of suspended or dissolved substances to be oxidized and reduced, and which might otherwise settle out at the bottom, or float at the 45 top, or causes concentration variations in other ways. A suitable cell for this purpose is that shown and described in my U. S. Letters Patent No. 1,388,216.

50 The process itself will be described as adapted to the electrolytic oxidation of an acceptor, such as anthracene to anthraquinone, and reduction of a different acceptor such as azoxybenzol to benzidine by one 55 electrolysis. Such oxidation and reduction, producing two different products, I find can

be attained by the use of an electrolyte containing chromium ions both as anodic and cathodic catalysers, depolarizers or carriers of oxygen and hydrogen to the said acceptors. Other suitable depolarizers or catalysers, such as vanadium, manganese, cerium or titanium ions, or combinations thereof; or other suitable ions possessing several different valencies or degrees of oxidation, may 60 be utilized, and in concentrations suitable for or customary in electrolytes.

In the oxidation of anthracene and the reduction of azoxybenzol with an electrolyte containing chromium ions, electricity 70 for the electrolysis is to be supplied in any well known manner to a suitable cell or cells (not shown); and the initial electrolyte, both as to the anode and cathode portions, may consist of an aqueous solution 75 of sodium bichromate and sulphuric acid in the proportions of one pound of the former and two pounds of the latter to each gallon of solution, although other suitable portions may, of course, be used. At the initial stage 80 of the process, the electrolysis is to be continued until substantially all of the sodium bichromate of the cathode portion of the electrolyte has been reduced to chromium sulphate. Or, as an alternative, the cell may 85 be initially supplied with an electrolyte containing chromium sulphate and sulphuric acid, such as spent chromium liquors resulting from oxidation of anthracene to anthraquinone. In such case, the spent liquors will 90 or may contain chromium sulphate, sodium sulphate and sulphuric acid in proportions substantially the same as those resulting from the electrolytic reductions of the sodium bichromate and sulphuric acid solution hereinbefore specified. Electrolysis 95 prior to the introduction of acceptors, for oxidation and reduction, will then not be necessary.

With a catholyte which is substantially 100 free from sodium bichromate and an anolyte consisting either of the specified solutions of sodium bichromate and sulphuric acid, or, chromium sulphate, sodium sulphate and sulphuric acid, there is added to the catholyte, azoxybenzol, as for example, in the proportion of one-half to one pound thereof per gallon of catholyte. To the anolyte, there is added anthracene in the proportion, for example, of one-half to one pound thereof to each gallon of anolyte. Electrolysis 105 is then started, resumed or continued, ac-

accompanied preferably by a vigorous agitation of the anolyte and catholyte in such a way that the acceptors are well distributed throughout the body of the electrolyte. Suitable current density will be three to five amperes per square decimeter of either electrode surface; and a suitable temperature is 60°-90° C. The anode and cathode may be of lead, which I have found acts satisfactorily for the oxidation and reduction specified. In other electrolyses electrodes of other metal may be found preferable.

The electrolysis under these or other suitable conditions may be maintained until substantially all of the azoxybenzol has been reduced and substantially all of the anthracene is oxidized. In such an electrolysis, chromium ions act as a depolarizer or carrier of the hydrogen liberated at the cathode to the azoxybenzol, reducing it eventually to hydrazobenzol, which latter compound is converted into benzidine by the sulphuric acid present in the electrolyte. The end result is that all or substantially all of the azoxybenzol is converted into benzidine sulphate, which is insoluble in and may be separated from the catholyte, as by filtration. At the same time, the bichromate ions formed at the anode, under the conditions of the electrolysis, oxidize the anthracene suspended in the anolyte to anthraquinone, which is also insoluble in and may readily be separated from the anolyte, as by filtration.

The end result, of the electrolysis, therefore, is a catholyte containing chromium sulphate, sodium sulphate and sulphuric acid, and an anolyte which will be of substantially the same composition, if sufficient anthracene has been used to reduce all the sodium bichromate originally present or formed by the electrolysis. It is desirable that this be done in order to have for the next operation or for the continuation of the same operation, an electrolyte which is substantially free from sodium bichromate. If all the sodium bichromate has not been used up in the oxidation of the anthracene, an additional amount of anthracene may be oxidized with the resulting anolyte, by filtering off the anthraquinone formed and using enough anthracene to reduce substantially all of the remaining sodium bichromate to chromium sulphate.

It will also be understood that the oxidation of the anthracene to anthraquinone by the bichromate electrolyte formed at the anode may be entirely effected, if desired, subsequent to the electrolysis and outside the electrolytic apparatus, as by collecting an amount of the electrolyte containing sufficient bichromate to oxidize chemically any desired amount of anthracene. This operation may be accomplished by well known methods and under well known conditions

in a suitable vat or other container (not shown) and extraneous to the electrolytic apparatus.

In either case, the anolyte, remaining from filtering off the anthraquinone if sufficient anthracene has been used, will be substantially free of sodium bichromate. However, its concentration in sulphuric acid will have increased due to the migration of SO_4^2- ions from the catholyte to the anolyte during the electrolysis; and the sulphuric acid concentration of the catholyte will have correspondingly diminished. For this reason, the liquors or the electrolysis should be reversed after each operation, that is to say the anolyte liquors should be used as a catholyte liquor and the catholyte liquor as the anolyte liquor in the continuation of the operation or the succeeding electrolysis, whereby the concentrations in sulphuric acid will tend to be restored by the said migration of SO_4^2- ions.

The concentration of sulphuric acid in the catholyte will, moreover, be reduced during electrolysis, by the combination of sulphuric acid with the benzidine to form benzidine sulphate, as aforesaid. During the electrolysis, therefore, or after the separation of the benzidine sulphate from the catholyte, a sufficient amount of sulphuric acid is to be added to the catholyte portion of the electrolyte to replenish the amount of sulphuric acid removed in combination as benzidine sulphate. After this has been done, the remaining catholyte is then to be used as the anolyte for a continuation or the next operation of the process, as aforesaid.

Operating in cycles in this manner, the electrolyte will maintain substantially its initial concentration in chromium and sulphuric acid ions during any series of operations; and repeated reductions of azobenzol and repeated oxidations of anthracene can be effected each by one electrolysis, using the same electrolyte over and over again if desired.

It will be understood that azobenzol or other azo or azoxy derivatives or homologues may be so reduced, and that other compounds than anthracene may be so oxidized. It is not necessary, moreover, that the final product should be solid and substantially insoluble in the resulting electrolyte, although that is desirable; for oxidation and reduction products, which can be separated by solvents immiscible in the electrolyte, or by other suitable means, may be produced by the novel process.

It will be understood that in using the word catalyser I intend to imply any ion or ions which will either act catalytically or as a depolarizer and carrier of oxygen and hydrogen in electrode processes, to oxidize or reduce less active acceptors; and that by the word acceptors I imply any substances

which will be respectively oxidized or reduced with the formation of separable products by the anodic and cathodic catalysts.

I am aware that separate oxidation and reduction, at different times, of certain compounds has been heretofore effected by means of electrolytes containing the same ion; but such oxidations and reductions have been carried out separately, with resultant loss of oxygen or hydrogen in each reduction or oxidation. For a number of years it has been the aim of chemists to effect such an oxidation and a reduction by one electrolysis; but this result has first been achieved, so far as I am aware, only by the herein described invention.

I claim:—

1. The process of electrolytic oxidation of one product and electrolytic reduction of another product, which consists in electrolysing an electrolyte separated into an anolyte and catholyte and containing ions capable of acting as anodic and cathodic catalysts, introducing into the anolyte and catholyte liquors acceptors capable of being respectively oxidized and reduced thereby and of forming products separable therefrom, and separating the resulting products.

2. The process of electrolytic oxidation of one organic product and electrolytic reduction of another organic product, which consists in electrolysing an electrolyte separated into an anolyte and catholyte and containing ions capable of acting both as anodic and cathodic catalysts, introducing into the anolyte and catholyte liquors acceptors capable of being respectively oxidized and reduced thereby and of forming products separable therefrom, and separating the resulting products.

3. The process of electrolytic oxidation of one product and electrolytic reduction of another product, which consists in electrolysing an electrolyte separated into an anolyte and catholyte and containing ions capable of acting both as anodic and cathodic catalysts, subsequently adding to the anolyte and catholyte liquors and while continuing the electrolysis acceptors capable of being respectively oxidized and reduced thereby and of forming products separable therefrom, and separating the resulting products.

4. The process of electrolytic oxidation of one product and electrolytic reduction of another product, which consists in electrolysing an aqueous solution of a chromium compound and sulphuric acid separated into an anolyte and catholyte, introducing into the anolyte and catholyte liquors acceptors capable of being respectively oxidized and reduced thereby and of forming products separable therefrom, and separating the resulting products.

5. The process of electrolytic oxidation of

an oxidizable product and electrolytic reduction of a reducible product, which consists in electrolysing an aqueous solution of sodium bichromate and sulphuric acid separated into an anolyte and catholyte, introducing, after the substantial reduction of the sodium bichromate of the catholyte portion, into the anolyte and catholyte liquors acceptors capable of being respectively oxidized and reduced thereby and of forming products separable therefrom, and separating the resulting products.

6. The process of electrolytic oxidation of an oxidizable product and electrolytic reduction of a reducible product, which consists in electrolysing an aqueous solution of sodium bichromate and sulphuric acid in the proportion of one (1) pound of the former and two (2) pounds of the latter per gallon of solution, separated into an anolyte and catholyte, introducing, after the substantial reduction of the sodium bichromate of the catholyte portion, into the anolyte and catholyte liquors acceptors capable of being respectively oxidized and reduced thereby and of forming products separable therefrom, and separating the resulting products.

7. The process of electrolytic oxidation of an oxidizable product and electrolytic reduction of a reducible product, which consists in electrolysing an aqueous solution of sodium bichromate and sulphuric acid in the proportion of one (1) pound of the former and two (2) pounds of the latter per gallon of solution, separated into an anolyte and catholyte, and at a temperature of from 60° to 90° C., introducing, after the substantial reduction of sodium bichromate of the catholyte portion, into the anolyte and catholyte liquors acceptors capable of being respectively oxidized and reduced thereby and of forming products separable therefrom, and separating the resulting products.

8. The process of electrolytic oxidation of one product and electrolytic reduction of another product, which consists in electrolysing an electrolyte separated into an anolyte and catholyte and containing ions capable of acting both as anodic and cathodic catalysts, introducing into the anolyte and catholyte liquors acceptors capable of being respectively oxidized and reduced thereby and of forming products separable therefrom, separating the resulting products, replenishing ions depleted in the electrolysis, and repeating the operation.

9. The process of oxidation of anthracene to anthraquinone and reduction of benzol compounds to benzidine, which consists in electrolysing an electrolyte separated into an anolyte and catholyte and containing ions capable of acting both as anodic and cathodic catalysts, introducing anthracene

into the anolyte and the benzol compound into the catholyte, and separating the resulting products therefrom.

10. The process of electrolytic oxidation 5 of anthracene to anthraquinone and the electrolytic reduction of azoxybenzol to benzidine, which consists in electrolysing an aqueous solution of sodium bichromate and sulphuric acid, introducing anthracene into 10 the anolyte and azoxybenzol into the catholyte, and separating the anthraquinone and benzidine sulphate from the respective liquors.

11. The process of electrolytic oxidation 15 of anthracene to anthraquinone and electrolytic reduction of azoxybenzol to benzidine, which consists in electrolysing an aqueous solution of sodium bichromate and sulphuric acid, introducing anthracene into the anolyte 20 and azoxybenzol into the catholyte, separating the anthraquinone and benzidine sulphate from the respective liquors, and replenishing the supply of sulphuric acid of the anolyte.

25 12. The process of electrolytic oxidation of one product and electrolytic reduction of another product, which consists in electrolysing an electrolyte separated into an anolyte and catholyte and containing ions capable of acting both as anodic and cathodic 30 catalysts, introducing into the anolyte and catholyte liquors acceptors capable of being respectively oxidized and reduced thereby and of forming products separable therefrom, separating the resulting products, and repeating the operation with anolyte as catholyte and catholyte as anolyte.

13. Electrolytic oxidation and reduction 40 process, with separated anolyte and catholyte and common catalyst ions, which includes the step of introducing therein acceptors capable of being respectively oxidized and reduced thereby and of forming products separable therefrom.

45 14. A process of electrolysis for the production of two products, which consists in

preparing an electrolyte containing ions capable of acting as anodic and cathodic catalysts, electrolysing so as to produce an anolyte and catholyte, adding thereto acceptors capable of being respectively oxidized and reduced thereby and of forming products separable therefrom, and separating the resulting products.

15. A process of electrolysis for the production of two organic products, which consists in preparing an electrolyte containing ions capable of acting both as anodic and cathodic catalysts, electrolysing so as to produce an anolyte and catholyte, adding thereto acceptors capable of being respectively oxidized and reduced thereby and of forming products separable therefrom, and separating the resulting products.

16. A process of electrolysis for the production of two products, which consists in preparing an electrolyte containing ions capable of acting both as anodic and cathodic catalysts, electrolysing so as to produce an anolyte and catholyte, adding thereto acceptors capable of being respectively oxidized and reduced thereby and of forming products separable therefrom, separating the resulting products, and using the anolyte as catholyte and the catholyte as 75 anolyte in a subsequent operation.

17. The process of electrolytic oxidation of anthracene to anthraquinone and the electrolytic reduction of azoxybenzol to benzidine, which consists in electrolysing an 80 aqueous solution of sodium bichromate and sulphuric acid, introducing anthracene into the anolyte and azoxybenzol into the catholyte, separating the anthraquinone and benzidine sulphate from the respective liquors, 85 and using the anolyte as catholyte and the catholyte as anolyte in a subsequent operation.

Signed at New York in the county of New York and State of New York this 31st 90 day of March, A. D. 1923.

CHARLES J. THATCHER.
